(57) **CLAIM**

We claim the ornamental design for an interactive mobile multimedia communications device, as shown and described.

DESCRIPTION

FIG. 1 is a front view of the mobile multimedia communications device.

FIG. 2 is a back view of the mobile multimedia communications device.

FIG. 3 is a side view of the mobile multimedia communications device; and,

FIG. 4 is an isometric view of the mobile multimedia communications device.

The broken line showing in the figures is for illustrative purposes only and forms no part of the claimed design.
